[57] CLAIM

The ornamental design of a ceiling fan, as shown and
described.

DESCRIPTION

FIG. 1 is a bottom perspective view of a ceiling fan
showing my new design;

FIG. 2 is a top plan view thereof;

FIG. 3 is a bottom plan view thereof; and

FIG. 4 is a side elevational view thereof, the sides adja-
cent and opposite being substantially similar in appear-
ance.

FIG. 1

FIG. 2

FIG. 3

FIG. 4
